PHONOGRAPHIC APPARATUS

Original Filed June 29, 1940

UNITED STATES PATENT OFFICE

2,326,499

PHONOGRAPHIC APPARATUS

Frank E. Runge, Indianapolis, Ind., assignor to
Radio Corporation of America, a corporation
of Delaware

Original application June 29, 1940, Serial No.
343,116. Divided and this application May
28, 1941, Serial No. 395,524

6 Claims. (Cl. 274—47)

This invention relates to phonographic apparatus of the type adapted to record sound upon a blank disc for immediate playback, and more particularly to the mechanism therein for collecting the shavings or thread produced during the groove-cutting operation, the present application being a division of my copending application Serial No. 343,116, filed June 29, 1940, now Patent No. 2,262,148, and assigned to Radio Corporation of America.

In recent years, there have come into rather extensive use sound-recording machines employing blank discs in which sound grooves may be cut by means of a suitable cutter which removes a thread or shaving during the cutting operation. These discs are usually made of a suitable base material, such as aluminum, coated with several layers of surface material, such as nitrocellulose lacquers or the like. These surface materials are of a nature such that the threads cut therefrom tend to curl up and gather around the cutter, and unless they are removed, they may accumulate around the cutter to an extent such as to interfere with the proper cutting operation.

Various mechanisms have been proposed heretofore for removing the shavings or thread produced during the cutting operation. Such devices usually embody suction means, blowers, or the like, all of which are relatively complicated and expensive. Other mechanisms which are less complicated have also been proposed, but these do not remove the threads very effectively.

The primary object of my present invention is to provide an improved thread remover, in phonographic apparatus of the type set forth above, which will not be subject to the disadvantages of prior art thread removers.

More particularly, it is an object of my present invention to provide an improved shaving or thread remover for collecting the shavings cut in the blank disc by the cutting stylus.

It is also an object of my present invention to provide an improved thread remover which is simple in construction, inexpensive in cost, and which will not require apparatus extraneous to that normally employed in the recording machine.

In accordance with my present invention, I provide a lead screw on a frame member one end of which is mounted on the motor board and the other end of which rests on the turntable and carries the driving mechanism which couples the rotating turntable to the lead screw for delivering power thereto. A suitable carriage which

is arranged to coast with the lead screw carries the signal-translating device which includes a cutting stylus adapted to cooperate with a record blank on the turntable. Included in the coupling between the turntable and the lead screw is a somewhat spool-shaped member which rests on the record blank and has driving engagement with the turntable, the spool-shaped member being arranged concentrically with the turntable and record blank and occupying an area on the record substantially equal to the central label area found on conventional records. Due to the resilience of the thread cut from the blank and its tendency to curl, it winds itself around the neck of the spool-shaped member in the form of a ring during the cutting operation, and when this operation is completed, the spool-shaped member may be uncoupled from the turntable and the ring of threads or shavings may be easily slipped off and discarded.

The novel features that I consider characteristic of my invention are set forth with particularity in the appended claims. The invention itself, however, both as to its organization and method of operation, as well as additional objects and advantages thereof, will best be understood from the following description of one embodiment thereof when read in connection with the accompanying drawing in which

Figure 1 is a front elevation, partly in section, showing a recording machine which includes a thread collector in accordance with my present invention, and

Figure 2 is a fragmentary sectional view taken on the line II—II of Figure 1.

Referring more particularly to the drawing, I have shown, in Figure 1, a motor board 1 provided with a pair of openings 3 and 5 through the former of which extends a motor shaft 7 terminating in a spindle 9 to which a turntable 11 is suitably secured, and the latter of which has extending therein an internally threaded sleeve 13 which is secured to the motor board. Threaded into the sleeve 13 is a bushing 15 which rotatably receives a downwardly extending pin 17 on a yoke 19, the yoke 19 carrying a pair of conically tipped bearings 20 which pivotally support one end of a frame 21. By turning the bushing 15 in the threads of the sleeve 13, the bushing 15 can be raised or lowered and locked in any desired position by means of a set screw 23, and since the yoke 19 is rotatable horizontally within the bushing 15 and the frame 21 is rotatable vertically on the bearings 20, it is obvious that the frame 21 is universally adjustable relative to the

turntable 11 to cause the frame to assume any desired angular relation with respect to the turntable.

The upper end of the spindle 9 is conically tipped and has resting thereon a shaft 25 journaled in the frame 21 and formed with a conical seat or bearing in its lower end. The shaft 25 carries a worm 27 which meshes with a gear 29 fixed to a short shaft 31. The turntable 11 is provided with a plurality of circumferentially distributed openings 33 which are radially spaced from the spindle 9 and which receive driving pins 35 threaded into a somewhat spool-shaped coupling member 37 having a neck or central portion 37a intermediate its length for a purpose presently to be set forth.

The shaft 25 extends down through the coupling member 37 and is connected thereto by means of a diametrically extending cross pin 39, the lower conical seat of the shaft 25, which is formed on a greater angle than the conical tip of the spindle 9, resting on the spindle tip. The construction is generally similar to that disclosed and claimed in the copending application of Raymond F. Brady, Serial No. 276,604, filed May 31, 1939, now Patent No. 2,276,459, and assigned to Radio Corporation of America. It will be obvious from the foregoing description that power may be transmitted from the motor shaft 1 to the turntable 11, thence through the pins 35, the coupling member 37 and the cross pin 39 to the shaft 25 and its worm 27 which, in turn, drives the gear 29 and its shaft 31.

The frame member 21 includes a pair of tie bars 41 and 41a and rotatably carries a lead screw 43 which is connected to the shaft 31 by a one-way spring clutch 45 one end of which is fixed to the shaft 31 and the other end of which is wound loosely on the adjacent end of the lead screw 43. The spring clutch 45 is so arranged that when the shaft 31 begins to turn it tends to wind the spring 45 tightly around the lead screw and thereby drives it. The opposite end of the lead screw 43 extends beyond the frame member 21 and has secured thereto a handle 47 by means of which the lead screw 43 may be turned manually in the same direction as the spring 45 tends to turn it for rotating the lead screw at a greater speed than is provided by the gearing 22-29, as is sometimes desirable.

Mounted on the lead screw 43 for both rotation and longitudinal sliding movement thereon is a combined supporting and operating sleeve 49 provided with a forwardly extending operating handle 51. A mounting sleeve 53 is freely mounted on the supporting sleeve 49 and has a pair of downwardly extending arms 53a on the lower end of which is pivotally carried a signal-translating device or recorder head 55 carrying a cutting stylus 57, all as set forth more fully and claimed in my above-identified copending application. Inasmuch as the details of this particular mounting mechanism are not material to the present invention, it is not believed necessary to describe them in greater detail. Suffice it to say, however, that, by manipulating the handle 51, the cutter head 55 may be either raised from or lowered down onto a record blank R supported on the turntable 11, as the case may be.

During the recording operation, the stylus 57, in engagement with the record blank R, cuts a thread 59 therefrom to form a groove 61 in the blank disc. As the shaving 59 is removed from the blank, it tends to curl up toward the center of the blank and then reverse itself back toward

the cutting stylus. In conventional machines, the thread then accumulates around the stylus and, in many instances, interferes with the further proper recording. By providing the spool-shaped coupling member 37, however, the shaving or thread 59 will wind itself loosely around the neck portion 37a thereof as the turntable rotates, and the thread will collect on the coupling member in the form of a ring eccentrically to the axis of the coupling member 37 and on a diameter somewhat greater than the base of the coupling member 37, as clearly shown in Figure 2. When the recording operation is completed, the handle 51 is raised to remove the cutter head 55 from engagement with the record blank R, whereupon the entire mechanism may be lifted from the record blank by pivoting the frame member 21 around the pivots 20, and the ring of shavings which has accumulated on the shaving collector 37 can be slipped off easily therefrom.

From the foregoing description, it will be apparent to those skilled in the art that I have provided an improved shaving collector which has many advantages not found in prior art devices of this nature. Although I have shown and described but one embodiment of my invention, I am fully aware that many other modifications thereof are possible. I desire it to be understood, therefore, that my invention is not to be limited except insofar as is made necessary by the prior art and by the spirit of the appended claims.

I claim as my invention:

1. In signal-recording apparatus of the type employing a rotatable turntable and a disc record blank supported thereon, the combination of a signal-translating device movable over said blank and including a cutting element for cutting a groove in said blank by removal of shavings therefrom, and a spool-shaped member resting on said blank concentrically with said turntable, said member having driving engagement with said turntable whereby to be driven thereby and having its portion of reduced diameter in sufficiently close relation to said turntable to enable said shavings to wind around it as it rotates whereby to collect said shavings thereon.

2. In signal-translating apparatus of the type employing a rotatable turntable and a disc record blank supported thereon, the combination of a lead screw located at a relatively remote point from the exposed surface of said blank, means coupling said turntable to said lead screw for imparting rotation to said lead screw from said turntable, a driven member cooperating with said lead screw and adapted to be driven thereby, and a signal-translating device carried by said driven member and including a cutting element for cutting a groove in said exposed blank surface by removal of shavings therefrom, said coupling means including a member disposed in close proximity to said exposed blank surfaces and rotatable with said turntable for receiving shavings cut by said cutting element during the cutting operation.

3. In signal-translating apparatus of the type employing a rotatable turntable and a disc record blank supported thereon, the combination of a lead screw located at a relatively remote point from the exposed surface of said blank, means coupling said turntable to said lead screw for imparting rotation to said lead screw from said turntable, a driven member cooperating with said lead screw and adapted to be driven thereby, and a signal translating device carried by said

driven member and including a cutting element for cutting a groove in said exposed blank surface by removal of shavings therefrom, said coupling means including a substantially spool-shaped member disposed in close proximity to said exposed blank surface for receiving shavings cut by said cutting element during the cutting operation.

4. The invention set forth in claim 3 characterized in that said spool-shaped member is concentric with said turntable and rests on said blank, and characterized further in that said member is of a diameter such that it rests only on the central portion of said blank.

5. In signal-translating apparatus of the type employing a rotatable turntable and a disc record blank supported thereon, the combination of a lead screw extending across said turntable in a relatively elevated plane above said record blank, means coupling said turntable to said lead screw for imparting rotation to said lead screw from said turntable, a driven member cooperating with

5 said lead screw and adapted to be driven thereby, and a signal translating device carried by said driven member and including a cutting element for cutting a groove in said blank by removal of shavings therefrom, said coupling means including a substantially spool-shaped member disposed in closer proximity to said blank than said lead screw for receiving shavings cut by said cutting element during the cutting operation.

10 6. The combination with a recording mechanism employing a rotatable turntable and means arranged over said turntable for cutting a thread-like strand from the upper surface of a disc record blank arranged on said turntable in forming a recording thereon of a thread-removing attachment comprising a spool-shaped member axially aligned with said turntable and having driving engagement therewith, said thread being adapted to wind itself around the neck of said member during the recording operation and while said turntable and member are rotating
